CAR COUPLER

Russell J. Wittmer, Cleveland Heights, Ohio, assignor to National Malleable and Steel Castings Company, Cleveland, Ohio, a corporation of Ohio

Application August 10, 1938, Serial No. 224,028

8 Claims. (Cl. 213—104)

This invention relates to car couplers and more particularly to guiding means for use with car couplers such as will prevent jack-knifing of the adjacent couplers during the coupling operation.

My invention may be advantageously used with the type of coupler shown in Robinson Patent 1,904,171, issued April 18, 1933, which patent shows a car coupler particularly adapted for use on mine cars. It has been found that couplers of the general type shown in the Robinson patent may lie in such angled positions relative to each other that as two couplers move towards each other in a coupling operation the contact between them causes the couplers to jack-knife, that is, to increase their angled position relative to the car. When the couplers are in this position it is impossible to properly couple them without first separating the cars and moving the couplers back to positions in which jack-knifing will not occur. These couplers will jack-knife under certain conditions even when they are positioned within the gathering range of the couplers and it may occur on either straight or curved track.

Jack-knifing occurs for the reason that the first contact between the couplers falls within the angle formed by the center line of a coupler and a line drawn between the points on the cars about which the couplers pivot. Continued movement of the couplers towards each other, instead of straightening them out so that they can complete the coupling operation, will merely increase the angular relation of each coupler with respect to its car, and cause them to reach positions in which coupling becomes impossible.

It is an object of the present invention to eliminate jack-knifing by a construction which provides for contact between mating couplers such as will move the couplers upon contact thereof, in a direction that will allow them to slide into coupled engagement.

My invention can be best understood from the following description and drawings, in which:

Figure 1 is a view of two couplers embodying the invention, each of which is angled with respect to its own car, the cars being illustrated in the position they assume on straight track.

Figure 2 is a view similar to Fig. 1, but showing adjacent cars angled with respect to each other, representing curved track.

Figure 3 is an enlarged plan view of the coupler in Fig. 1.

Figure 4 is an elevational view of the coupler shown in Fig. 3.

Figure 5 is a plan view showing two of the couplers in coupled position.

Figure 6 is a view showing a modified form of the invention applied to a pair of couplers which are shown in coupled position.

Figure 7 is an elevational view of the couplers shown in Fig. 6.

Figure 8 is a plan view of the couplers of Fig. 6 angled with respect to their cars and in the act of being guided to coupled position.

Figure 9 is an enlarged plan view of the modified form of coupler of Fig. 6.

Figure 10 is an elevational view of the coupler shown in Fig. 9.

Figure 11 is a front view of the coupler shown in Fig. 9; and

Figure 12 is a plan view of a pair of couplers showing a slightly modified form of the invention.

Referring to Figs. 1 to 5, inclusive, there is shown a coupler having a head 2 which comprises a buffing jaw 3, and a pulling and guiding jaw 4 connected by a buffing face 5 arranged at an angle to the longitudinal center line of the coupler. The pulling jaw has a laterally extending recess 6 to receive the complementary jaw 3 of an opposing coupler head, and its pulling face 7 engages a complementary face 8 on the buffing jaw of the opposing coupler head. The lock 9 may be similar to that shown in the aforesaid Robinson patent and is adapted to be moved rearwardly in the coupler head to permit passage of jaw 3 of the opposing coupler during a coupling operation. The operating lever 10 is adapted to retract the lock for uncoupling two couplers.

Fig. 1 shows two adjacent couplers pivotally mounted at points 11 and 12 on adjacent cars 13 and 14, respectively. The couplers are shown in angled position such that the point of contact between jaw 3 of one coupler with jaw 4 of the opposing coupler is to the side of a line drawn through pivots 11 and 12, towards the longitudinal center lines A of the couplers. In accordance with my invention an abutment 15 is formed on each coupler rearwardly of jaw 3 and has a front surface 16 extending substantially parallel to the front surface 17 of jaw 4 of the coupler. A rib 18 may be provided to reinforce abutment 15. It will be observed that contact between abutment 15 of the coupler on car 13 and the jaw 4 of the coupler on car 14 occurs on the opposite side of line X—X than the contact between jaws 3 and 4 of said couplers. If we assume in Fig. 1 that abutment 15

were not present, then continued movement of the cars towards each other will exert forces on the couplers tending to cause the latter to form a greater angle with the center lines of their respective cars, and the point of contact between jaws 3 and 4 to move away from line X—X. During this movement jaw 3 of the coupler on car 13 will usually slide to the position shown in dot-dash lines in Fig. 1 and in this position the couplers will not straighten and can not be properly interengaged. Angular movement of the couplers may continue until they contact abutments 19 on the car structures. The addition of abutment 15 counteracts the aforesaid movements for the reason that the point of contact between jaw 4 and abutment 15 is on the side of line X—X opposite to the point of contact between jaws 3 and 4, thus causing a force to be exerted, the direction of which is laterally away from the center lines of the couplers. Therefore, the contacting points of jaw 4 will slide along jaw 3 and the outer face of abutment 15, causing the couplers to straighten themselves and move to the coupled position shown in Fig. 5.

The same action will take place in Fig. 2 wherein it is noted that the couplers are substantially centered each with respect to its own car. Even so, it will be observed that the point of contact between jaw 3 of one coupler and jaw 4 of the opposing coupler is on the side of a line joining pivots 11 and 12, such as will cause jack-knifing of the couplers. The provision of abutment 15 causes contact between the forward face thereof and jaw 4 of the opposing coupler to be on the opposite side of line X—X and effectively prevents jack-knifing and results in straightening of the couplers, as previously described in connection with Fig. 1. In each of the cases shown in Figs. 1 and 2, the initial contact between jaws 3 and 4 will lie in the angle between the longitudinal center line of one of the couplers and a line joining pivots 11 and 12. If it were not for abutment 15 the couplers would slide to the position shown in dot-dash lines in Fig. 1 and thus prevent the couplers from straightening. However, instead of contacting as above, my invention provides for contact on the opposite side of the line joining pivots 11 and 12 from the center lines of the couplers, which causes a force to be exerted in a direction that will straighten the couplers and allow them to couple. Furthermore, if the couplers were angled with respect to the cars a greater distance than is shown in Figs. 1 or 2, the contact would first be between jaw 4 of one coupler and abutment 15 on the opposing coupler, which would initially cause rotational movement between the couplers until jaws 3 and 4 contact each other after which the coupler would straighten in the manner previously described. It is not essential that surfaces 16 and 17 be parallel, as will be apparent from Fig. 12, which shows surfaces 16' and 17' at an angle to each other. Guiding surface 16' will function in the same manner as previously described in connection with surface 16.

Referring now to Figs. 6 to 11, inclusive, the guiding means for straightening the couplers embodies certain changes in the buffing and pulling jaws thereof but the principle of the straightening action is the same as in the form previously described. In this modified form of the invention the buffing jaw 25 is projected laterally and forwardly to form an abutment

26 of less vertical height than jaw 25. This abutment is reinforced by rib 27. The pulling jaw on the opposite side of the coupler is cut away at its midportion to form upper and lower jaws 28 and 29, respectively, between which is received the abutment 26 of an opposing coupler. Upper jaw 28 is formed on its bottom with an upwardly and outwardly sloping surface 30 and likewise lower jaw 29 is formed with an upper surface 31 sloping forwardly and downwardly. These surfaces assist in vertically gathering the mating couplers by engagement with the upper or lower surfaces of an opposing abutment 26 on a mating coupler. Extending laterally and rearwardly from the rear end of the slot formed by jaws 28 and 29 is an abutment 32 which has a front surface 33 substantially parallel to surface 34 of abutment 26. Abutment 32 may be reinforced by a rib 49. As can be readily seen from Figs. 6 and 7, when two couplers are coupled, abutment 26 lies between jaws 28 and 29 of the opposing coupler and adjacent the abutment 32 thereof.

In Fig. 8 a pair of couplers are shown in the act of coupling and pivoted on cars 36 and 37 at points 38 and 39, respectively. It will be observed that the contact between abutment 26 of the coupler on car 36 and abutment 32 of the coupler on car 37 is on the side of line Y—Y joining pivots 38 and 39 as will cause the couplers to rotate and slide on each other in a direction that will straighten them out and thus be in a position to couple in the same manner as in the embodiment shown in Figs. 1 to 5. Although Fig. 8 shows the adjacent cars on straight track, the same action will take place if on curved track, similar to Fig. 2.

It will be observed that relative vertical movement between the couplers is limited by contact between abutment 26 and surfaces 30 and 31 of the opposing coupler. If desired, this movement can be substantially entirely eliminated by making the height of abutment 26 substantially the same as the vertical distance between the inner ends of surfaces 30 and 31.

In both of the embodiments shown the couplers are constructed to transmit buffing blows therebetween along the longitudinal axis of the coupler and clearance is therefore provided between surfaces 16 and 17 in the coupler shown in Figs. 1 to 5, and 33 and 34 in the coupler shown in Figs. 6 to 11 to relieve the guide wings from buffing stresses. However, if desired, the guide wings may be constructed to receive buffing blows, in which case the aforesaid clearance would be eliminated.

Although I have shown and described my invention in connection with couplers particularly adapted for use with mine cars its application is not so limited and it may be advantageously used wherever difficulty is experienced with jack-knifing as herein described.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In combination, a pair of pivotally mounted car couplers each having a plurality of transversely spaced fixed jaws adapted to interengage when said couplers are coupled together, guiding

surfaces on said jaws for normally guiding said couplers into coupled engagement and guiding means extending diagonally rearwardly of one of said jaws having a surface thereon at an angle to the guiding surfaces on said jaw adapted, when said couplers are horizontally angled relative to each other, to engage the opposite jaw of said other coupler on the side of a line drawn through the pivots of said couplers opposite to the longitudinal center lines of said couplers.

2. A pivotally mounted car coupler having a transversely disposed buffing face and fixed jaws at each end thereof having surfaces thereon in pulling engagement with complementary jaws of an opposing coupler, said jaws normally being adapted to guide said couplers into interlocking engagement, and means extending rearwardly and outwardly of one of said jaws adapted to contact the opposite jaw of an opposing coupler on the side of a line drawn through the pivots of said couplers opposite to the longitudinal center lines thereof to guide said couplers into engagement when said coupler is angled relative to an opposing coupler to such an extent that the initial contact of said jaws would be ineffective to prevent jack-knifing.

3. A pivotally mounted car coupler having a transversely disposed buffing face and fixed jaws at each end thereof having surfaces thereon in pulling engagement with complementary jaws of an opposing coupler, said jaws normally being adapted to guide said couplers into interlocking engagement, and means extending rearwardly and outwardly of one of said jaws adapted to contact the opposite jaw of an opposing coupler on the side of a line drawn through the pivots of said couplers opposite to the longitudinal center lines thereof to guide said couplers into engagement when said coupler is angled relative to an opposing coupler to such an extent that the initial contact of said jaws would be ineffective to prevent jack-knifing, said means being normally spaced from said opposite jaw of an opposing coupler when said couplers are in coupled engagement.

4. A pivotally mounted car coupler having a fixed jaw on either side of its center line for pulling and buffing engagement with the complementary jaw of an opposing coupler, said fixed jaws being normally adapted to align said couplers laterally and to align said couplers angularly to a limited extent, an auxiliary guiding wing extending laterally and rearwardly from one of said fixed jaws and adapted to contact one of said fixed jaws on an opposing coupler head on the side of a line drawn through the pivots of said couplers opposite to the center lines thereof to bring said couplers sufficiently into alignment so that the said fixed jaws are effective to complete the alignment, said auxiliary guiding wing being so located with respect to said fixed jaws that it is maintained out of contact with said opposing coupler when the couplers are intercoupled.

5. A pivotally mounted car coupler having a pair of transversely spaced fixed jaws adapted to intercouple with similar jaws on an opposing pivoted coupler, one of said first-named jaws being bifurcated and adapted to receive an extension on the opposite jaw of said opposing coupler, and guiding means extending diagonally rearwardly of said coupler from the inner end of said bifurcated portion, said guiding means being adapted to engage said extension on the side of a line drawn through the pivots of said couplers opposite to the longitudinal center lines thereof for aligning said couplers during the coupling operation.
- 10 6. A pivotally mounted car coupler having a laterally extending buffing face and fixed jaws at each end thereof having pulling engagement with complementary jaws on an opposing pivoted coupler, one of said jaws being bifurcated and the other of said jaws having an extension adapted to enter the bifurcated jaw of an opposing coupler, and guiding means extending diagonally rearwardly of said bifurcated jaw, said means having a forward face substantially parallel to said buffing face adapted to engage said extension of an opposing coupler on the side of a line drawn through the pivots of said couplers opposite to the longitudinal center lines thereof for aligning the couplers during the coupling operation.
- 15 7. A pivotally mounted car coupler having a laterally extending buffing face and fixed jaws at each end thereof having pulling engagement with complementary jaws on an opposing pivoted coupler, one of said jaws being bifurcated and the other of said jaws having an extension adapted to enter the bifurcated jaw of an opposing coupler, and guiding means extending diagonally rearwardly of said bifurcated jaw, said means having a forward face to the rear of and substantially parallel to said buffing face adapted to engage said extension of an opposing coupler on the side of a line drawn through the pivots of said couplers opposite to the longitudinal center lines thereof for aligning the couplers during the coupling operation.
- 20 8. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 25 9. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 30 10. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 35 11. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 40 12. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 45 13. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 50 14. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 55 15. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.
- 60 16. A pivotally mounted car coupler having a pair of fixed jaws adapted to intercouple with complementary jaws on an opposing pivoted coupler, one of said jaws comprising upper and lower spaced portions having inner walls converging towards the rear of said coupler, guiding means comprising a member extending diagonally rearwardly from the inner ends of said walls, and said other jaw having a portion extending diagonally forwardly thereof and adapted to enter the space between the upper and lower portions of the opposite jaw of an opposing coupler and adapted to engage said member on the side of a line drawn through the pivots of said couplers opposite to the longitudinal center lines thereof for aligning the couplers during the coupling operation.

RUSSELL J. WITTMER.
